APPARATUS FOR DRYING, HEATING, OR COOLING

Filed Sept. 6, 1928

Inventor:

Frederic Joseph Warden-Stevens

By: *Edward George*

Attorney.

UNITED STATES PATENT OFFICE

FREDERIC JOSEPH WARDEN-STEVENS, OF LONDON, ENGLAND

APPARATUS FOR DRYING, HEATING, OR COOLING

Application filed September 6, 1928, Serial No. 304,344, and in Great Britain March 18, 1927.

This invention applies more particularly to improvements in methods of, and apparatus for, drying or heating coal for combustion, carbonization or distillation; coke for combustion; limestone or chalk for pulverizing or burning; stone to be coated with tar or other substance or liquid; ores for milling or furnace processes or any other lump, granular, broken or crushed materials requiring to be dried and/or heated; and for cooling coke, clinker, ashes, slag, lime, cement or other granular, lump or broken materials requiring to be cooled.

This invention applies more particularly to methods in which hot gases or air are used for drying or heating and cold air or cooled gases are used for cooling, and either by being forced or induced through or passed over the mass of lump, granular, broken or crushed material to be treated, and either in direct or indirect, or partially direct and partially indirect contact with such material, and either in conjunction partially or not with steam or water to aid the treatment.

And this invention has particular importance to the methods and forms of apparatus described in patent specification No. 1,424,565 in so far as it provides in particular for the better and more even distribution of the gases or air over the surface or through the mass of material to be treated, and for reduction or variation of the resistance to the passage of the gases or air through the material according to its form or condition or requirements. And this invention also provides for facilitating the flow or passage of the material by gravity in the course of its treatment through the apparatus and for collection of solid or liquid matter contained

in the gases or air which form the treating medium. To describe the improvements and apparatus comprising my invention I will refer to apparatus of a vertical or inclined form through which the material to be treated passes by its own weight or gravity or partially so and during its passage is subjected to a heating or cooling treating medium passing in a transverse or diagonal direction. For improvements in the distribution of the gases or air at the intake of

such to the apparatus, whether it be forced or induced into the apparatus, I provide a form of screen or screens in the inlet chamber of the apparatus for directing or dividing or distributing the gases or air, such screen or screens being either fixed or movable as required or one or more fixed and the other or others movable and which also serve to obstruct dust or moisture contained in the treating medium, or a form of plate or plates, cone or cones, cowl, scroll or vanes, which may be either fixed or subject to motion, for the purpose of spreading, distributing, directing or guiding the treating medium over the whole, part or parts of the face or surface of the mass of the material through which it is to be forced or induced, and which may also serve to obstruct dust or moisture if contained in the gases or air forming the treating medium. At the exit for the treating medium from the apparatus I provide a fixed or movable baffle or baffles, or deflecting plate or plates of such form that instead of the gases or air taking a direct path from the face or surface of the material through the mass of which it is forced or induced and being confined to the area of the exit, it is more uniformly distributed over the face of the material and the form of baffle or plate may also serve to obstruct, separate or collect dust or liquid matter which may be contained in the treating medium after passing through the material under treatment. In addition to, or substitution for, the last named form of plate or baffle I provide in the exit chamber of the apparatus a form of screen or screens such as I have stated I provide in the intake chamber of the apparatus, but not necessarily of exactly similar form, the purpose of the screen in the exhaust chamber having similar objects to the baffle or baffles or plates last referred to, to enable separation of solid or liquid matter which the treating medium has collected during its passage through the material under treatment; such screens also aid the distribution or direction of the treating medium through the material under treatment. To reduce the resistance to the passage of the material by gravity through the

apparatus, depending on the form or condition of the material I provide for a reciprocating movement of the retaining walls or louvres of the treating chamber through which the treating medium passes.

And, in the treatment of some materials liable to bind or cake together I sometimes provide within the mass of the material one or more stationary or movable horizontal tubes or rods, and either with or without projections, which assist to keep the material gravitating through the apparatus as well as to create voids for the treating medium to penetrate through the mass of the material thus serving a dual purpose.

To reduce the pressure or suction necessary for the treating medium to be forced or induced through the material to be treated, in case of excessive obstruction, for example material in the form of fine grains, or liable to cake, I provide, through the mass of the material, vents for the treating medium through the mass of the material and to enable the treating medium to obtain access to the interior of the mass of the material and to penetrate it.

I will now describe improvements and apparatus according to my present invention with reference to the accompanying drawings.

Fig. 1 is an elevation view shown in section, and illustrating a suitable arrangement of means for reciprocating the walls of the treating chamber and loosening and forming vents in the material and directing the treating medium through the commodity.

Fig. 2 is a sectional elevation showing a modified form of means for directing the treating medium through the material.

Figs. 3 and 4 show in diagrammatic sectional elevation two methods of utilizing the outlet of the treating medium for improving its distribution through or over the material and collection of solid or liquid matter contained in the treating medium.

Fig. 5 shows in elevation, and partly in section, a suitable arrangement of vertical angle bars on the outlet and inlet sides for the treating medium for aiding its distribution and collecting matter from the treating medium; also horizontal specially formed angle bars for forming vents in the material.

Fig. 6 is a plan view, in part section, of Fig. 5.

Fig. 7 is a perspective view of a particular design of angle bar for forming vents in the material.

Figs. 8 and 9 show respectively in cross sectional elevation another method of loosening the material to be treated, and

Fig. 10 shows in diagrammatic elevation another method of reciprocating the walls of the treating chamber by simultaneously altering the angles of the louvres forming the walls of the treating chamber.

Referring to the drawings, in Fig. 1 the material to be treated is delivered into a hopper 1 so that it gravitates between two containing walls 2 and 3 such walls consisting of narrowly spaced transverse or longitudinal channels, strips or louvres arranged in cross section at about an angle of 45 degrees the inner edges of the louvres being the lower edges. The treating medium for drying, heating or cooling, which may be a suitable gas, is delivered through an inlet 4 into one side of a housing 5, the inlet 4 having a revolving cowl 6 driven from any suitable source, for instance by the action of the passage of the treating medium, and which distributes such treating medium in desired directions vertically and horizontally before passing through the louvres 3 so that the said treating medium operates effectively over the whole of the inlet surface of the louvred wall adjacent to the inlet with a consequent larger drying, heating or cooling area, or can be diverted in any desired direction by closing one or other of the openings of the cowl casing or other convenient manner such as by movable screens, shutters, dampers or baffles within the housing. The treating medium after passing through the material is drawn or forced out of an outlet 7.

Instead of a rotating cowl 6 a series of fixed or movable vanes can be arranged connected with the inlet 4, these vanes having such a configuration that the said treating medium has a spiral flow imparted to it to distribute it over the surface of the louvred wall adjacent to the inlet 4. To assist in maintaining the distribution of the treating medium a pair of symmetrically arranged plates 2a may be used to divide the passage to the outlet 7 into three separate angular passages which spreads the treating medium passing through the treating chamber, or a series of conical baffles 9, see Fig. 4, can be provided over the outlet side of the housing for the treating medium, these baffles being spaced as shown but increasing in diameter towards the outlet end, the innermost baffle being closed with a part spherical portion 10 at its centre but the others being open at their centres for the passage of the said treating medium. In Fig. 3, instead of conical plates 9, one or more annular plates 11 is or are provided each arranged in between a pair of discs 12 slightly spaced from the plate 11 but covering its central opening in an axial direction so that the said treating medium has to take a somewhat sinuous path out of the apparatus. The plate 11 and discs 12 are preferably formed with concentric corrugations as shown to trap any matter carried from the material by the said treating medium. In Fig. 2 is shown the use of a conical plate 13 which may be perforated for distributing the said treating medium as it enters the apparatus this plate if desired being

flared at its periphery and fixed as shown adjacent to the flanged pipe fixed to the inlet 4.

In order to reduce the resistance of the flow of the material through the apparatus as well as to facilitate the passage of the treating medium through the material the louvres constituting the walls 2 and 3 are reciprocated or moved vertically by supporting them in frames connected at the top and bottom to transverse horizontal bars B carried at their ends to slides A, see Fig. 1, the lower bar B is connected by a link C to a lever D oscillating about a pivot D' at one end and connected at its other end by a link D² to a crank disc F driven from a wheel H. Bars B move in slots A provided in the end walls of the housing 5, and they may be arranged to move together parallel or alternately one up and one down. Owing to the additional free dust and surface exposed which will result due to the loosening of the said material and the consequent reduction of resistance to the treating medium and increase of surface contact between the treating medium and the material, it is desirable to provide means for collecting matter acquired by the treating medium during its passage through the said material. In Figs. 5 and 6 I have shown a screen a at the outlet side of the housing for collecting any matter contained in the treating medium; a similar screen b also being shown in Fig. 6 at the inlet side, said screens also serving for the better distribution of the treating medium. Each screen consists of a number of parallel slightly spaced bars of V or other suitable channel section, for instance arcuate section, the channel sides of the bars being directed towards the inlet side for the said treating medium so that a large proportion of the matter collected by the said treating medium will be trapped in the channels of the said bars.

To obviate undue resistance of the material from interfering with the requisite passage of the treating medium therethrough as an alternative or to assist the operation of the said reciprocating rods or tubes, louvres or walls the treating chamber can have disposed horizontally or angularly across it a number of angle or channel section bars d as shown in Figs. 1, 5 and 6 the bars having their ends close to the said louvres if fixed transversely but they may be fixed longitudinally as shown in the figures last named. These bars are V section with their apexes uppermost as shown and as illustrated in Fig. 7 have a portion or portions of the side removed so that the said treating medium may circulate into the material through the spaces obtained by the said removed portions, the channel end being open nearest the louvres on the inlet side but may be closed at the end adjacent to the exit side louvres. These bars may also serve for dividing the

chamber into sections transversely or longitudinally.

One method of mechanically reducing the resistance of the material is shown in Figs. 8 and 9. In this arrangement rods or tubes 21 which latter may preferably be perforated are reciprocated across the direction of passage of the material. The rods or tubes 21 are slideable in guides 22a and are connected at one end to an arm 27a which is rocked about a fulcrum point 28 the requisite rocking action preferably being obtained by a rotating drum 29 having a spiral groove in its periphery in which engages a pin carried by the end of the arm 27a the drum 29 being driven from any suitable source, for instance gearing 31, part of which can be mounted on a shaft 32, see Fig. 8, carrying radial blades 33 operating in the outlet 34 of the apparatus for obtaining an intermittent discharge of the material. In this instance the rods or tubes can carry projections 21a and if the arc of the movement of the arm 27a is excessive which is improbable the said rods or tubes could be connected to the said arm by links 90 to compensate for such arc of movement. If tubes are used 21 and 21a can be perforated for better distribution of the treating medium into the bulk or mass of the material.

In order to assist the passage of the treating medium or as an alternative means of loosening the said material the louvres 2 and/or 3 can as hereinbefore described, with reference to Fig. 1, be reciprocated. The method shown in Fig. 1 is suitable with some materials and under some conditions, but in Fig. 10 is shown another method in which louvres 37a each carry at one end and on each side a lateral pin 35 of circular section, or a roller mounted on a lateral pin, the pins 35 or rollers 35 sliding in fixed horizontal grooves 36 provided in the end walls of the treating chamber. The other ends of the louvres 37a are secured to pivot pins 37 connected to a vertical bar 38 which is reciprocated in a vertical path thereby gradually changing the inclination of the louvres. The bar 38 can be reciprocated by rotating a nut 39 in alternate directions and threading an extension 40 of the bar 38 through the said nut. The nut 39 can be part of a bevel gear wheel 41 meshing with a further gear wheel 42 driven in alternate directions from any suitable source. This method not only provides for loosening the material but for varying the distance between the louvres and their angle and the width of the space for the material. At certain stages in the operations, the louvres by the foregoing mechanism can be arranged to overlap each other so as to completely isolate the treating chamber from the said treating medium, so that the said treating medium only obtains access to the material at the appropriate or most suitable moments. Likewise the maximum

opening of the louvres and the space available for the material can be adjusted by regulating the amount of movement of the bar 38, to compensate for different results required and conditions with different materials to be treated. The patent hereinbefore mentioned does not detract from the advantages of my present invention which is primarily based upon experience with the apparatus described in the said patent and as a result of such experience I am convinced it is a desideratum to provide means for varying the resistance of the flow of the material in the bulk and to loosen or form voids or vents therein for the said treating medium if the desired results are to be efficiently obtained. Further, "loosening," as I term it, of the material when in bulk form to be readily effective should if possible have combined with it means for spreading the said treating medium over as large an area of the material as possible because obviously if for instance in Fig. 1 the treating medium was not distributed in the manner described or in some equivalent manner a large amount of the benefit it is desired to obtain by "loosening" the material would be lost as by reason of this "loosening" of the material there is a greater transfer of the heating and cooling properties from the treating medium to the material and vice versa. If the material is loosened in the bulk to facilitate its passage through the treating chamber and formed with voids to vary the resistance of the passage of the treating medium therethrough there is much greater heat transfer than for instance in the apparatus described in Patent No. 1,424,565.

What I claim is:

40. 1. In apparatus for drying, heating or cooling materials, a vertical treating chamber down which the material passes by gravity, an inlet for a treating medium on one side of the chamber and an outlet for such medium on the opposite side, two sets of louvres, one each side of the treating chamber, and two separated grid like sets of angle section bars, one between the said louvres and said inlet, and the other between the louvres and the outlet, the apices of the angle section bars being directed towards the said outlet, and means for moving each set of louvres up and down, and a number of bars across the space between the louvres such bars being movable up and down with the louvres.
45. 2. In apparatus for drying, heating or cooling materials, a vertical treating chamber down which the material passes by gravity, an inlet for a treating medium on one side of the chamber and an outlet for such medium on the opposite side, two sets of louvres, one on each side of the treating chamber, and two separated grid like sets of angle section bars, one between the said louvres

and said inlet and the other between the louvres and the outlet, the apices of the angle section bars being directed towards the said outlet, and means for moving each set of louvres up and down, and horizontal rods parallel with said louvres and carrying external projections and arranged for movement within the treating chamber.

In witness whereof I have signed this specification.

FREDERIC JOSEPH WARDEN-STEVENS.
